REVOLVING DOOR

Edmund Peremi, Manhasset, and Charles Kish, Elmhurst, N. Y., assignors to General Bronze Corporation, Long Island City, N. Y., a corporation of New York

Application June 1, 1935, Serial No. 24,492

7 Claims. (Cl. 20—18)

This invention relates to revolving doors, and more particularly to revolving doors of the type in which provision is made of a governor for limiting the speed at which the door can be turned.

5 Features of the invention relate to the provision of improved governing means and improvements in the arrangement and relation of the governing means with reference to the door proper.

10 The present application is a continuation in part of our pending application, Serial No. 633,584, filed September 17, 1932, for Revolving doors.

15 Other objects and advantages will hereinafter appear.

In the drawings forming part of this specification,

20 Fig. 1 is a diagrammatic view, partly in side elevation, and partly in vertical section, showing a door housing with a trolley mounted above the same and the door depending from said trolley, the door being shown folded and swung to one side so as to release a latch which normally holds the trolley and door against bodily movement to 25 the side of the door opening;

Fig. 2 is a fragmentary plan view of a door supporting trolley and governor mechanism mounted thereon, the cover of the governor mechanism being removed;

30 Fig. 3 is a detail vertical section on the line 3—3 of Fig. 2;

Fig. 4 is a detail vertical sectional view on the line 4—4 of Fig. 2, and

35 Fig. 5 is a longitudinal vertical section taken approximately on the line 5—5 of Fig. 2.

Referring to the drawings in detail, 20 is a door enclosure which comprises the curved wall sections 21, the ceiling 22 and the floor 23. In the ceiling 22 is a slot 24 for the door column.

40 Mounted above the ceiling are channelled rails 25 constituting a track for the door trolley 26 which is provided with wheels 27 running on the track. Fixed to the track are stops 30 and 31 provided with striker blocks 32 and 33. Mounted

45 on the trolley are latches 34, 35 adapted to engage with the respective striker blocks. The latches are pivoted on pins 36 and each is provided with an operating arm 37. The door comprises a central column 40 on which are pivotally

50 mounted in any suitable manner a plurality of leaves 41, preferably four in number. Means are provided whereby the leaves may be locked in radial position when the revolving feature of the door is being utilized, such means being well un-

55 derstood and therefore not being illustrated in

detail herein. The leaves may also be folded together in any well understood manner so as to permit the door to be moved to one side of the door opening. For instance, the leaves may be folded in pairs extending diametrically from the door column. The column 40 is suspended from the trolley by means of a block 45 fixed on the column which bears on a suitable anti-friction bearing 46 which is mounted in a carrier member 47. The carrier member 47 is supported on the trolley frame in such manner as to permit of a limited universal movement of the door column so as to permit the latter to hang vertically and insure the free movement of the door in its housing and also to permit actuation of the latches in the manner hereinafter explained. To secure the universal movement described any well known means may be employed. In the construction illustrated, the bearing member 47 is provided with cylindrical bearing surfaces 48 which rest in correspondingly shaped grooves in the gimbal ring or cradle 49. The gimbal ring or cradle is provided with trunnions 50 which rest in recesses 51 in the side members of the trolley frame. The block 45 and door column 5 are preferably further supported in true position with respect to the carrier 47 by means of an anti-friction bearing 55. In the construction illustrated, the carrier block 47 also carries a governor housing 60 to be described more in detail below and the corner 61 of this governor housing is adapted to engage the arm 37 of the latch 35 to release such latch when the door column is pushed towards the right as shown in Figure 1 so as to tilt the carrier block 47 and gimbal ring 35 on the trunnions 50. When the door column is swung in the opposite direction a horn 62 carried by the carrier block 47 is adapted to engage the arm 37 of the other latch 34.

Assuming the door to be in central position in the door housing and the door column to be vertical, the latch 35 will be in engagement with the striker block 33 and the trolley locked in central position over the door housing. At its lower end the column will be held in central position by the usual bottom pivot 56 fitting in a socket in the floor. If it be desired now to move the door to one side of the door housing, the leaves will first be folded up as shown in Figures 1 and 2 and the bottom pivot retracted from the floor socket in the usual manner. The door is then simply pushed towards the right. This will first cause the column to swing to one side as shown in Figure 1 and will bring the corner 61 of the governor housing into engagement with the latch arm and 55

release the latch 35, whereupon the door and trolley will move to the right. When the door reaches the limit of travel it will be stopped by engagement of the end of the trolley with the striker block 32 and at the same time the latch 34 will ride over the surface of the striker block and engage behind the same, thereby locking the trolley in its side position. To return the door to central position the door is merely pulled out towards the center whereby at first it will swing to the left and release the latch and then the trolley will move towards the center until the latch 35 engages with the striker block 33.

In order that the speed of rotation of the door may be regulated to a desired maximum, and spinning prevented, governing means are preferably provided, and we have shown in Figures 2 to 5 a preferred form of friction regulating means for this purpose. As here illustrated, the carrier member 47 of the trolley is provided with a governor housing 60. Fixed on the upper end of the door column 40 is a gear 90 which extends into the governor housing and meshes with a pinion 91 mounted on a shaft 92 supported in a bearing 93 in the lower part of the governor housing and in a bearing 94 in the cover plate of the housing. Also fixed to the shaft 92 is a rotary table 100 which carries the governor mechanism. A pair of brake shoes 101 are provided which are pivoted on pins 102 which are mounted in the table and in bracket plates 103 fixed to the table by means of screws 104 and 105. The brake shoes are provided with strengthening ribs 110 and with surfaces of suitable friction material 111 which engage with the inner surface 112 of the housing, such surface constituting a stationary brake drum. Centrifugal means are provided for causing the brake shoes to engage the brake drum, such means comprising the weights 115 mounted on the ends of levers 116 which are pivoted on pins 117 in the bracket plates 103. The levers 116 are preferably channel shaped, as shown in Figures 3 to 5 and are provided with lugs 120 which engage with lugs 121 on the brake shoes, as shown in Figure 2, whereby the centrifugal force of the weights 115 is applied to the brake shoes in multiplied ratio, depending upon the relative lengths of the lever arms.

Each weight 115 is secured upon the associated lever 116 by means of a screw 116a. In order to enable the effectiveness of the weights to be adjusted through a wide range, provision is made in the lever 116 of a plurality of threaded bores 116b which may be selectively used so as to mount the weight at different distances from the pivot pins 117 upon which the lever is mounted.

For holding the brake shoes out of engagement with the brake drum until the desired maximum speed has been reached and in order to regulate such speed, springs 125 are provided which bear against surfaces 126 on the bracket plates 103 and which are universally connected to the brake shoes by means of rods 127 engaging pins 128 on the ends of the brake shoes. The tension of the springs 125 may be adjusted by means of nuts 130 screwing on the ends of rods 127. The springs draw the brake shoes away from the brake drum until a sufficient speed of rotation is reached to cause the centrifugal force of the weights 115 to overcome the spring tension, whereupon the braking force will be applied and the speed of the door checked. Until this speed is reached no braking effect is produced and the door revolves freely. By adjusting the tension of the springs by means of the nuts 130 the speed

at which the braking force will be applied may be varied.

It is a feature that the rods 127 are connected to the ends of the brake shoe ribs and that they extend non-radially so that they may pass the 5 governor shaft. This arrangement has several advantages. The rods 127 and the springs 125 may be made long enough to afford a very substantial range of spring adjustment. It is unnecessary for the rod to be passed through an 10 aperture in the lever 116 for connection with the brake shoe. The rod, moreover, is so located that it does not interfere with adjustment of the weight to different positions along the lever 116.

While we have illustrated and described in detail certain preferred forms of our invention, it is to be understood that changes may be made therein and the invention embodied in other structures. We do not, therefore, desire to limit ourselves to the specific constructions illustrated, 20 but intend to cover our invention broadly in whatever form its principle may be utilized.

We claim:

1. In a revolving door, a door enclosure, a track mounted above the same, a trolley mounted on said track, a carrier mounted on said trolley to have limited universal movement with respect thereto, a door column carried by said carrier, door leaves pivotally mounted on said column, centrifugal friction brake mechanism mounted on 30 said door column carrier and driving connections from said door column to said friction brake mechanism, said centrifugal friction brake mechanism and driving connections moving with said door column carrier as said door column carrier may be tilted by movements or adjustments of said door column whereby said driving connections are unaffected by movements of the door column carrier.

2. In a revolving door, a door enclosure, a track mounted above the same, a trolley mounted on said track, a carrier mounted on said trolley to have limited universal movement with respect thereto, a door column carried by said carrier, door leaves pivotally mounted on said column, a 40 governor housing carried by said carrier having a fixed braking surface therein, centrifugally controlled friction means for engaging said braking surface, a rotatable shaft carried by said governor housing for driving said means, a pinion on said shaft and a gear on the upper part of said door column for driving said pinion, said governor housing, centrifugal brake means, rotatable shaft and pinion moving with said door column and door column carrier whenever the same are tilted 45 whereby the driving connection between the door column and the centrifugal brake means is unaffected by tilting movement of the carrier.

3. A door supporting trolley for revolving doors comprising a wheeled carriage, a cradle mounted to tilt thereon about a horizontal axis, a door column carrier mounted on said cradle to tilt about an axis at right angles to the axis of tilt of said cradle, a friction governor housing mounted on said door column carrier and adapted to tilt therewith and having a fixed braking surface therein, centrifugal braking means mounted in said housing and having a movable braking surface adapted to be brought into braking engagement with said fixed braking surface by centrifugal action, and driving means for said centrifugal braking means adapted to be driven from a door column carried by said door column carrier.

4. In a revolving door, a door enclosure, a track

- mounted above the same, a trolley mounted on said track, a carrier mounted on said trolley to have limited movement with respect thereto, a door column rotatably supported by said carrier, 5 door leaves pivotally mounted on said column, a gear on the upper end of said door column, a governor housing mounted horizontally upon said carrier and not extending substantially outside the lateral bounds of the track, the inner wall of 10 the housing constituting a brake drum, a vertically disposed shaft rotatably mounted in said housing, spur gearing forming a driving connection between the gear on the door column and said shaft, a horizontal rotary table mounted on said shaft and centrifugally controlled friction means supported on the table and within the housing for 15 engaging said brake drum.
5. In a revolving door, a door enclosure, a track mounted above the enclosure, a trolley mounted 20 on said track, a carrier mounted on said trolley to have limited movement with respect thereto, a door column rotatably supported by the carrier, door leaves collapsibly mounted on the column, a gear on the upper end of the door column, a 25 governor housing mounted horizontally upon said carrier and confined substantially to the lateral bounds of the track, the inner wall of the housing constituting a brake drum, a vertically disposed shaft rotatably mounted in said 30 housing, spur gearing forming a driving connection between the gear on the door column and said shaft, a horizontal rotary table mounted on said shaft, and centrifugally controlled friction means supported on the table and within the housing for 35 co-operating with the brake drum to check the speed of rotation of the door when a predetermined speed has been reached comprising brake shoes pivoted on the table, weight levers pivoted on the table inside the brake shoes, weights carried by the weighted levers, springs for normally holding the brake shoes out of engagement with the brake drum, tension rods connecting the 40 springs to the ends of the respective brake shoes, and means for adjusting the stress of the springs.
6. In a revolving door, a door enclosure, a track mounted above the enclosure, a trolley mounted 45 on said track, a carrier mounted on said trolley to have limited movement with respect thereto, a door column rotatably supported by the carrier, door leaves collapsibly mounted on the column, a gear on the upper end of the door column, a 50 governor housing mounted horizontally upon said carrier and confined substantially to the lateral bounds of the track, the inner wall of the housing constituting a brake drum, a vertically disposed shaft rotatably mounted in said housing, spur gearing forming a driving connection between the gear on the door column and said shaft, a horizontal rotary table mounted on said shaft and centrifugally controlled friction means supported on the table and within the housing for 55 co-operating with the brake drum to check the speed of rotation of the door when a predetermined speed has been reached comprising brake shoes pivoted on the table, weight levers pivoted on the table inside the brake shoes, weights carried by the weighted levers, springs for normally holding the brake shoes out of engagement with the brake drum, tension rods connecting the 60 springs to the ends of the respective brake shoes, and means for adjusting the stress of the springs, 65 said tension rods being universally connected to the ends of the brake shoes and extending non-radially past the center of the table.
